COMBINED BRUSH AND COMB

Benjamin Oshman and David Oshman,
New York, N. Y.

Application August 18, 1938, Serial No. 225,508

15 Claims. (Cl. 132—86)

This invention relates to a combined brush with combs, of the type wherein these two elements are utilized simultaneously and in cooperation, for improved and efficient combing and brushing of the hair, and its principal object is to provide a simplified, efficient, conveniently operable, and improved article for this purpose.

Another object is to provide such article with improved means for mounting the combs thereon and demounting them therefrom, to permit efficient and convenient cleansing or renewal of the combs.

Another object is to provide such article with improved means for positively locking said combs in requisite place when in mounted position.

Other objects and advantages will hereinafter appear.

In the accompanying drawing—

Fig. 1 is a plan view of the article, with the brush partially broken away, showing the combs in operative position.

Fig. 2 is a transverse-sectional view, in an enlarged scale, of the article shown in Fig. 1.

Fig. 3 is a view similar to Fig. 2, but showing the combs in inoperative position.

Fig. 4 is a longitudinal cross-sectional view, showing a detail of the mechanism of this article.

Fig. 5 is a plan view, in a reduced scale, showing a modification of the invention.

The article 1 comprises the usual body 2, a handle 3, and a brush 4 set in said body, the latter being provided with a channelled chamber 5 that extends clear therethrough from side to side 6 thereof, as shown in Fig. 3. Within the chamber 5 and along the longitudinal centre line thereof is located a shaft 7 which is rotatably mounted in a bearing 8 and in a nut 9 lodged in a recess 10. Said shaft carries a pair of gears 11 that mesh with racks 12 forming part of a framing 13 adapted to receive a comb 14, and the gears 11 also mesh with upper racks 15 forming part of a framing 16 adapted to receive a comb 17. Upon rotation of shaft 7, therefore, in a clockwise direction as viewed in Fig. 3, the framings 13, 16 and the combs carried thereby are propelled within the chamber 5 toward the shaft to the concealed position shown in Fig. 3, while rotating the shaft backwardly projects the combs 14, 17 outwardly to the operative position shown in Figs. 1, 2. The shaft 7 is manipulated by a knurled cylinder 18 fixed thereon, which cylinder is set in a recess 19 provided in the body 2 near its junction with the handle 3 and protrudes through the surfaces of the upper side and underside of the body, as shown in Fig. 4. The racks 12, 15 are preferably guided by channels 20 formed in the chamber 5, and so proportioned that when the combs 14, 17 are moved fully to the inoperative position shown in Fig. 3 their terminals 21 abut against the channel-ends 22 to limit their motion

in this direction, while moving the combs to operative position causes the rack-terminals 23 to abut against the channel-ends 24 to similarly limit the movement of the parts in an opposite direction. To further assure the limitation of movement of the combs and the said parts, the cylinder 18 is mounted in its recess 19 to maintain the shaft 7 against longitudinal movement and the shaft-portion 1a and nut 9 are threaded and tapped, whereby rotation of the cylinder 18 in one direction causes the nut 9 to bind thereagainst and lock the shaft 7, Fig. 4, with the combs in inoperative position, while rotating the cylinder 18 oppositely causes the nut 9 to bind against the end 25 of recess 10, which thereby locks the shaft 7 with the combs in the operative position shown in Fig. 1.

Each of the combs is insertable into and removable from its receiving framing 13 or 16, and is held therein by the dove-tailed configuration 20 of the comb-back and the framing, Figs. 2, 3. The comb is inserted into the framing longitudinally through its end adjoining the rear end of the body 2, and when fully inserted the terminal 26 of the comb abuts against the ledge 27 of the body 2 to limit and position the comb in requisite location in the framing. A trigger 28 slidable in a recess 29 formed in the body 2 and impelled by a spring 30 is normally projected outwardly from the body and is located against the rear end 31 of the comb, in which manner the latter is insured against accidental withdrawal from its framing or dislocation. When it is desired to remove the comb for cleaning or renewal, the trigger is pressed back into its recess 29 and the comb may be then retracted or withdrawn from its framing.

According to the modification shown in Fig. 5, the shaft 7 extends from the body 2 clear through the brush-handle 3 and projects from the extremity 32 of the latter, whereat its terminal is formed as a knurled cylinder 33, similar to the cylinder 18. A collar 34 formed on the shaft 7 is seated in a registering recess 35 in the body 2 and maintains the shaft against longitudinal displacement. The shaft portion 1a adjacent to the cylinder 33 is threaded and carries a tapped square nut 36 which is slidable in a registering square recess 37 in the handle 3. Rotation of the shaft 7 in one direction, therefore, propels the nut 36 to bind against the cylinder 33 to lock the shaft, while reversing the rotation causes the nut to bind against the end 38 of recess 37 and locks the shaft against rotation in the opposite direction.

Variations may be resorted to within the scope of the invention, and portions of the improvements may be used without others.

Having thus described our invention, we claim—

1. A hair brush having the combination of a

- body for the brush, a pair of combs mounted in said body to slide inwardly to inoperative position and outwardly to operative position, a shaft mounted rotatably in said body, and means actuated by the rotation of said shaft to move said combs to operative and inoperative positions.
2. A hair brush having the combination of a body for the brush, a pair of combs mounted in said body to slide inwardly to inoperative position and outwardly to operative position, a shaft mounted rotatably in said body, a gear carried by said shaft, a rack carried by each of said combs meshing with said gear, and said shaft transmitting its rotation through said gear and racks to move said combs to operative and inoperative positions.
3. A hair brush having the combination of a body for the brush, a pair of combs mounted in said body to slide inwardly to inoperative position and outwardly to operative position, a shaft mounted rotatably in said body, means actuated by the rotation of said shaft to move said combs to operative and inoperative positions, and means to arrest the rotation of said shaft in either direction to limit the movement of said combs when in either of said positions.
4. A hair brush having the combination of a body for the brush, a pair of combs mounted in said body to slide inwardly to inoperative position and outwardly to operative position, a shaft mounted rotatably in said body, a gear carried by said shaft, a rack carried by each of said combs meshing with said gear, said shaft transmitting its rotation through said gear and racks to move said combs to operative and inoperative positions, and means to arrest the rotation of said shaft in either direction to limit the movement of said combs when in either of said positions.
5. A hair brush having the combination of a body for the brush, a pair of combs mounted in said body to slide inwardly to inoperative position and outwardly to operative position, a shaft mounted rotatably in said body, means actuated by the rotation of said shaft to move said combs to operative and inoperative positions, said shaft having a threaded portion, a tapped nut slidable on said portion by the rotation of said shaft, and means to limit the movement of said nut to thereby arrest the rotation of said shaft in either direction to limit the movement of said combs when in either of said positions.
6. A hair brush having the combination of a body for the brush, a pair of combs mounted in said body to slide inwardly to inoperative position and outwardly to operative position, a shaft mounted rotatably in said body, a gear carried by said shaft, a rack carried by each of said combs meshing with said gear, said shaft transmitting its rotation through said gear and racks to move said combs to operative and inoperative positions, said shaft having a threaded portion, a tapped nut slidable on said portion by the rotation of said shaft, and means to limit the movement of said nut to thereby arrest the rotation of said shaft in either direction to limit the movement of said combs when in either of said positions.
7. A hair brush having the combination of a body for the brush, a pair of combs mounted in said body to slide inwardly to inoperative position and outwardly to operative position, a shaft mounted rotatably in said body, a gear carried by said shaft, a rack carried by each of said combs meshing with said gear, said shaft transmitting its rotation through said gear and racks to move

said combs to operative and inoperative positions, guiding means for said racks, and abutments in said guiding means limiting the movement of said racks in either direction.

8. A hair brush having the combination of a body for the brush, a framing mounted in said body being slideable thereinto and outwardly therefrom, and a comb being attachable to and completely detachable from said framing for cleansing or renewal.

9. A hair brush having the combination of a body for the brush, a framing mounted in said body being slideable thereinto and outwardly therefrom, a comb being attachable to and completely detachable from said framing for cleansing or renewal, and means to propel said framing and comb into and outwardly from said body.

10. A hair brush having the combination of a body for the brush, a framing mounted in said body being slideable thereinto and outwardly therefrom, and a comb being attachable to and completely detachable from said framing by sliding longitudinally into and out of the framing.

11. A hair brush having the combination of a body for the brush, a framing mounted in said body being slideable thereinto and outwardly therefrom, a comb being attachable to and completely detachable from said framing by sliding longitudinally into and out of the framing, and means to lock said comb against longitudinal retraction from said framing.

12. A hair brush having the combination of a body for the brush, a framing mounted in said body being slideable thereinto and outwardly therefrom, a comb being attachable to and completely detachable from said framing by sliding longitudinally into and out of the framing, and a spring-pressed detent locking said comb against longitudinal retraction from said framing.

13. A hair brush having the combination of a body for the brush, a framing mounted in said body being slideable thereinto and outwardly therefrom, a comb being attachable to and completely detachable from said framing by sliding longitudinally into and out of the framing, and a spring-pressed detent mounted in said body locking said comb against longitudinal retraction from said framing.

14. A hair brush having the combination of a body for the brush, a pair of combs mounted in said body to slide inwardly to inoperative position and outwardly to operative position, a shaft mounted rotatably in said body, means actuated by the rotation of said shaft to move said combs to operative and inoperative positions, a handle for said brush, and said shaft extending longitudinally through said handle and projecting outwardly from its extremity for manipulation.

15. A hair brush having the combination of a body for the brush, a pair of combs mounted in said body to slide inwardly to inoperative position and outwardly to operative position, a shaft mounted rotatably in said body, a gear carried by said shaft, a rack carried by each of said combs meshing with said gear, said shaft transmitting its rotation through said gear and racks to move said combs to operative and inoperative positions, a handle for said brush, and said shaft extending longitudinally through said handle and projecting outwardly from its extremity for manipulation.
